UNITED STATES PATENT OFFICE.

LOGAN SNELL, OF SPOKANE, WASHINGTON.

GAS-ENGINE.

1,121,682.

Specification of Letters Patent. Patented Dec. 22, 1914.

Application filed June 10, 1912. Serial No. 702,787.

To all whom it may concern:

Be it known that I, LOGAN SNELL, a citizen of the United States, residing at No. 1901 Shannon avenue, Spokane, in the county of Spokane and State of Washington, have invented new and useful Improvements in Gas-Engines, of which the following is a specification.

My present invention relates to an internal combustion engine provided with a stationary cylinder and a revoluble cylindrical valve therein, the piston working within said cylindrical valve and the latter controlling ingress of combustible fluid to the interior of the cylinders and the egress of waste products of combustion therefrom.

The principal object of my invention is to provide an engine of the character described which is simple in construction, efficient in action and readily adjustable to take up wear upon the several parts.

Further objects of my invention are to provide for actuation of parts by mechanism which is practically noiseless in operation, yet equally efficient for the successful operation of the engine, as those producing a humming or clanking sound.

In the drawing, forming a part of this specification: Figure 1 is a side elevation of a four cylinder internal combustion engine, embodying my invention, parts being broken away and shown in central, vertical section to disclose details of construction. Fig. 2 is an end elevation of the engine disclosed in Fig. 1. Fig. 3 is a view similar to Fig. 2 but showing a face plate thereof removed, to disclose details of construction. Fig. 4 is a horizontal cross sectional view through the stationary cylinder of the engine and manifolds, the internal or revoluble cylinder being shown in plane. Fig. 5 is a central, vertical, transverse sectional view through one cylinder of the engine. Fig. 6 is an enlarged detail view in elevation of the revoluble cylinder.

Similar characters refer to similar parts throughout the views.

The stationary cylinders 7 are preferably cast integral with jacketing 8, and, as shown in Figs. 1 and 5 of the drawing, are each formed with a domical head 9. Each head 9 has a threaded aperture 10 formed therein and open preferably to the uppermost portion thereof, and spark admission ports 11 lead to the cylinders as indicated in dotted lines in Fig. 4 of the drawing.

The upper ends of ports 11 are internally threaded to receive spark plugs 12, the inner end of said ports being disposed as clearly shown in Fig. 1 of the drawing, in the domical head portion 9 of the cylinders. Induction ports 13, in communication with an inlet manifold 14, deliver to said cylinders 1, in the domical head 9 thereof, and exhaust ports 15, in communication with the exhaust manifold 16, also deliver to the domical heads 9 of the cylinders, these ports 13 and 15 being alined with respect to the transverse section of the head, and the said spark admission ports are also disposed to come within the upper and lower margins of said ports 13 and 15, for a purpose to be subsequently described.

Within the stationary cylinders 7 revoluble valve cylinders 17 are provided, one revoluble cylinder for each stationary cylinder. Each revoluble cylinder is provided with a domical head 18, formed complementary to the internal periphery of head 9 of the cylinders 7, and is recessed as at 19, at its uppermost portion. Oil delivering cups 20 are secured to the openings 10 of the stationary cylinder and deliver lubricant to the said recesses 19 which form, as it were, a reservoir for oil which may flow to the surfaces of the stationary cylinders 7 and revoluble cylinders 17, to facilitate rotation of the latter.

The lower end of each cylinder 17, which projects from the cylinders 7, is provided with a worm rack 21, and above this rack the cylinder is flanged as at 22, to fit in a complementary recess 23 of the stationary cylinder. Intermediate this flange 22 and the domical head 18, the cylinder 17 is recessed, as at 24, so as not to bear against the stationary cylinder, except at said flange 22 and head 18, thus reducing friction to a considerable extent.

Each revoluble valve cylinder 17 is provided with two ports 25 and 26, disposed diametrically opposite each other in the head 18, these ports being adapted to open the ports 13, 11 or 15, in successive relation.

In practice, it is desirable that the induction ports 13 be relatively smaller than the ports 25 or 26 in the cylinder 17, and that the exhaust ports 15 be relatively larger than the ports 25 and 26, and the relative positioning of ports 13 and 14, is such that to each half revolution of cylinder 17 one of the ports of the latter controls said induc-

tion and exhaust ports for the induction, compression, power and exhaust strokes of the engine, whereupon the other port in cylinder 17 becomes active as a controlling port, while the other passes through an arc of 180 degrees before it again becomes active as a control port. Thus, the ports act successively for opening the induction ports, the spark admission port and the exhaust ports, intermittently.

Within each cylinder 17 I provide a trunk piston 27, the exterior face of which is provided with a socket 28, adapted to receive a ball 29, carried by connecting rod 30, the ball being held in place by a two part bearing 31, held in place by bolts 32, and nuts 33, so as to be adjustable. The rod 30 is operatively connected with the crank 34 of a crank shaft 35, carried by bearings 36. The several cranks of the shaft 35 are disposed in the usual manner so that the engine has no dead center.

A crank case 37 may be provided enveloping the bearings 36, the lower end of the cylinder 17 and the rods 30, and may be provided with a longitudinally extending internally formed recess 38 to accommodate worms 39 and worm shaft 40, the worms meshing with worm racks 21 of the cylinders 17.

Adjacent one end of the engine, a casing 41 is provided, having a detachable face plate 42, said crank shaft 35 projecting into said casing and being provided with cranks 43 thereon disposed at quarters, said cranks being connected by rods 44, to crank 45 carried by worm shaft 40, disposed similarly to cranks 43. The ratio of movement of crank shaft 35 through cranks 43, rods 44, cranks 45, shafts 40, worms 39, worm rack 21 to cylinder 17, is such that the cylinders each make one revolution to every four revolutions of the crank shaft. It is to be observed that the means of transmitting movement of the crank shaft 35 to the drive shaft of the cylinders is through link mechanism and hence there is no clanking or perceivable sound as would be in the case of gears therebetween.

Preferably upon the bearings 36, I provide an adjustable cylinder support, for each cylinder, said support including a standard 46 secured in any suitable manner to said bearings, and a shoe 47 which contacts with the lower margin of the cylinder 17, this shoe being held in an adjusted position by a set screw 48 or any similar means. It is to be understood that each of the cylinders 17 has slight play within the corresponding stationary cylinder 7, but that when the engine is active, the tendency of the worm 39 to move the revoluble cylinder upwardly and the action of the explosions in the cylinder, force the domical head of the cylinder 17 closely in contact with the

internal periphery of the domical head 9, whereby a practically fluid tight engagement of the two portions is insured, adjacent the port openings. It is to be further noted that the cylinder 17 may be adjusted to take up any wear, and inasmuch as the ports are disposed in the domical heads of the cylinders, more efficient closure of the ports is provided than if they were disposed in the cylindrical walls of the cylinders.

The operation of the device is as follows:—As disclosed in Figs. 1 and 4, the first revoluble cylinder is positioned for the induction stroke; and the second revoluble cylinder is positioned for the exhaust stroke; the third revoluble cylinder is positioned for the compression stroke; and, the fourth revoluble cylinder for the power stroke. In practice, it is desirable that the exhaust ports of each cylinder be so disposed that it is entirely closed before the induction port is opened. In other words, when the piston is at the lowest point after the explosion, the exhaust port is slightly opened, but when the piston is at the highest point, the exhaust port is slightly closed. It is also desirable that the induction ports open and close when the engine is on center. Inasmuch as the spark is admitted into the cylinder through one of the ports 25 or 26, it is obvious that the charge can be fired when the piston is half way down or when half way up, giving ample latitude for advancing and retarding spark.

As shown in Fig. 4 of the drawing, the cylinders may be coupled in pairs, if desired, and fed by the same induction and exhaust ports, and in this figure, the first and third revolve contra-clockwise, while the second and fourth cylinders revolve clockwise.

I claim:

1. In an internal combustion engine, the combination of a cylindrical casing having a head with an oilway leading therethrough, and induction and exhaust ports, and a revoluble valve cylinder fitting into said casing having a head formed complementary to the said head of said casing, the head of said cylinder having a recess in its external periphery forming an oil reservoir and concentric with the axis of revolution of the cylinder, and said cylinder being adapted to open and close said ports of said casing.

2. In an internal combustion engine, the combination of a cylindrical casing having a head, induction and exhaust ports open to said head, and an annular groove adjacent the open end of said casing, a revoluble valve cylinder fitting into said casing and having a head formed complementary to said head of said casing with a port in said head for controlling the said port in said casing, said cylinder having a flange adapted to fit into said groove of said casing, said cylinder be-

ing reduced in diameter intermediate said head and flange, a standard adjacent said cylinder, an adjustable shoe carried by said standard and contacting with said cylinder 5 at its lower margin to retain the same in place, and means for driving said cylinder at a positive ratio.

3. In an internal combustion engine, the combination of a cylindrical casing having a 10 domical head with an oil way leading thereto, and induction and exhaust ports, and a revolute valve cylinder fitting into said casing having a domical head formed complementary to the said head of said casing, the 15 head of said cylinder having a recess in its external periphery forming an oil reservoir, said recess being concentric with the axis of revolution of said cylinder and said cylinder being adapted to open and close the said 20 ports of said casing, substantially as and for the purpose set forth.

4. In an internal combustion engine, the combination of a cylindrical casing having a 25 domical head, induction and exhaust ports open to said head and an annular groove ad-

jacent the open end of said casing, a revolute valve cylinder fitting into said casing and having a domical head formed complementary to the said head of said casing with a port in said head for controlling the said 30 ports of said casing, said cylinder having a flange adapted to fit in said groove of said casing, each cylinder being reduced in diameter intermediate said head and flange, a standard adjacent to said cylinder, an adjustable shoe carried by said standard and contacting with said cylinder at its lower margin to retain the same in place, a piston 35 in said cylinder, a crank shaft, means operatively connecting said piston with said 40 crank shaft to impart movement one to the other, and mechanism adapted to drive said revolute valve cylinder from said crank shaft at a positive ratio.

In testimony whereof I affix my signature 45 in the presence of two witnesses.

LOGAN SNELL.
